SINK STRAINER AND STOPPER AND THE
LIKE

Roy H. Zinkil, Oak Park, and Eugene W. Mar-
chand, Jr., Maywood, Ill., assignors to Crane Co.,
Chicago, Ill., a corporation of Illinois

Original application June 17, 1938, Serial No.
214,200. Divided and this application July 3,
1939, Serial No. 282,716

2 Claims. (Cl. 4—287)

Our invention relates to a more simple and economical sink strainer and stopper combination than has heretofore been available for the purpose set forth, in which the latter member is preferably embodied in a basket or tubular form with one end perforated for straining purposes and in which a suitable plug or stopper member carried by the strainer or basket is reciprocably movable therewith so as to serve as a shut-off valve enabling the filling of the basin of the sink with water, if desired. This application is a division of our copending application Serial No. 214,200, filed June 17, 1938.

Sink strainers of a previous type have been available in which the valve has been removable as an integral part of the strainer and in which the stopper member mounted in the strainer has been reciprocably movable upon similar movement by the handle, but to our knowledge no one has employed a construction in which, upon pivotal movement, the stopper handle is so actuated as to be positioned close to the top or rim of the basket strainer whether the valve is in the open or closed position, thus clearly avoiding the usual deposits within the strainer.

Another object of our invention is to provide a slot and crank mechanism fulcruming on an enclosing centerpiece of the strainer.

Other objects of the construction will become more readily apparent upon proceeding with the description in connection with the drawing, in which

Fig. 1 is a sectional assembly view of a preferred embodiment of our invention showing the construction of the slot and crank mechanism and showing the stopper in the raised or flow permitting position.

Fig. 2 is an external plan view.

Fig. 3 is a sectional assembly view taken at right angles to Fig. 1.

Like numerals refer to like parts throughout the various views of the drawing.

Referring to Figs. 1 and 2, the numeral 1 refers to a sink structure provided with the usual enamel coating 2 and having a drain opening 3 within which a conventional spud member 4 is applied, having one portion threaded as at 5, the lower portion of the sink at 6 having an abutting surface against which the gasket member 7 is positioned. A locking nut 8 is threadedly mounted upon the threads 5 of the spud member 4 in order to hold the latter in position within the sink drain opening 3 and also to make a water-tight joint preventing leakage past the periphery of the spud member within the sink opening proper. The

lower portion of the spud, as at 9, is preferably reduced and provided at its extreme lower end with threads 11 by means of which the usual connection is made to a pipe and trap (not shown). A conventional spider 12 is used therein to prevent relatively large particles from dropping through and into the sink discharge trap (not shown).

Resting upon the peripheral shoulder 13 there-within, a basket type of strainer 14 is mounted, the sides of which may be made solid, as indicated, or perforated, and the lower portion, as at 15, is preferably perforated to serve as a strainer. The strainer 14 is provided with a central hollow boss 16 within which the guide member or extension 17 of the valve closure member 18 is reciprocably journaled. The guide member 17 and the stopper member 18 are preferably detachably secured together, the latter member having a finished seat portion 19 for engagement, as shown in Fig. 3, with a similar surface or seat 21 upon the spud 4. The guide member 17 at its upper portion has a slotted part 22, as indicated at 23. A handle 24 is journaled within the central hollow boss as at 25 (Fig. 3), the handle 24 being provided with an offset portion 26 whereby, upon rotation of the handle 24 in an arcuate manner, the offset portion moves within the slot 23 so as to raise and lower the valve stopper 18. It will be noted that the handle proper is mounted completely within the hollow boss. The advantage of this construction lies in having a more sturdy arrangement insofar as durability is concerned, and also enables quick removal for purpose of repair and inspection by means of the threaded cap 27.

One embodiment of the invention is herein shown and described, but it is not desired to limit the invention to the particular embodiment shown. Therefore, we desire to be limited only to the extent of the appended claims.

We claim:

1. In a combined sink strainer and plug ar-
rangement, a hollow member secured within the
drain opening of a sink or the like, a plug serving
as a shut-off for the said drain opening and seat-
ing in the lower end of the said hollow member,
an upwardly concave strainer member removably
positioned above the said plug within the said
hollow member, a plug actuating handle piv-
otably mounted upon an upwardly projecting por-
tion of the said strainer and extending through
the said projecting portion, the said plug having
extensions cooperating with the end portions of
the said handle, whereby pivotal movement of
the said handle causes the said plug member to

act against a seating surface in the said hollow member.

2. The combination of a sink strainer and stopper including a tubular member within the drain opening of a sink or the like, a stopper serving as a shut-off for the said drain opening and seating within the said tubular member, a substantially cup-shaped strainer adapted to be

positioned within the said tubular member, a pivotally mounted handle for the said stopper member, the said strainer having centrally positioned journaling means for the said handle, the said stopper having an extension cooperating with the said handle within the said journaling means.

ROY H. ZINKIL.
